UNITED STATES PATENT OFFICE.

OSCAR H. PIEPER AND ALPHONSE F. PIEPER, OF ROCHESTER, NEW YORK.

SUPPORT FOR LIGHT-PROJECTING MEANS.

Application filed September 15, 1921. Serial No. 500,982.

This invention has to do with apparatus for supporting devices for projecting light rays such, for example, as X-ray tubes, one object of the invention being to provide a practical apparatus of this class for securely and flexibly supporting a light source so that it may be freely and easily adjusted by a slight effort of the hand thru a wide range of movement as may be found convenient in use.

Another object is to provide an apparatus of this variety combining with the flexible character of support described an advantageous arrangement and disposition of the parts for enclosing the light source to a large degree and thus protecting the same against injury. To these and other ends the invention consists in certain improvements and combinations of parts, all as will be hereinafter more fully described, the novel features being pointed out in the claims at the end of the specification.

In the drawings:

Figure 1 is a side elevation of an apparatus embodying the present invention.

Figure 2 is an elevation of the same as seen from the left in Figure 1.

Figure 3 is a top plan view of the same.

Figure 4 is an enlarged fragmentary section on the line 4^a—4^a of Figure 2.

Figure 5 is a section on the line 5^a—5^a of Figure 4.

Figure 6 is a side elevation of a modified form of a portion of the invention.

Figure 7 is a top plan view of the same, and

Figure 8 is an elevation as seen from the left in Figure 6.

Similar reference numerals throughout the several views indicate the same parts.

The present invention is in the nature of an improvement in apparatus such as that forming the subject matter of our co-pending applications Nos. 410,468 filed September 15, 1920, and 491,903 filed August 13, 1921, for supporting a source of light such as an X-ray tube. In the use of such a light source for making examinations of anatomical objects, as, for instance in dental X-ray photography, it is desirable to provide apparatus for securely supporting the light source or tube in a flexible manner so that it may be easily and conveniently swung by hand from one position to another and adjusted in the desired relation to the object

to be examined. To this end, as described in the said co-pending applications, there is preferably employed a supporting standard having an armed portion 10 the end of which is bifurcated to provide cheek bearing plates 11 between which is pivotally supported, on a bolt 12, a corresponding bearing plate 13 on a relatively movable section 14. Pivotally supported on the latter in any suitable manner for movement about an axis substantially perpendicular to the bolt 12 is a forked section 15 having branching arms 16 the lower ends of which carry trunnions 17 on which are pivotally supported the ends 18 of an adjustable frame 19.

Frame 19 is formed centrally into a looped portion 20, preferably of the substantially hexagonal shape shown, having opposite side portions 21 lying in parallel planes and providing guideways on which the light source is slidably adjustable. The guideways 21, as best shown in Figure 3, are preferably arcuate in shape so that as the light source is slidably adjusted along them it is also swung pivotally about a center which coincides approximately with the object to be examined, such adjustment being particularly adapted for making different views of a stereoscopic nature. At the ends of the guideways 21 the sides of the frame loop are curved transversely so that the end portions 18 of the frame extend along the opposite sides of the light source presently to be described.

The guideways 21 of the frame loop are preferably formed with V shaped tracks on which slide the correspondingly formed portions of a second frame which engages and supports the light source. As shown in Figure 4 the upper guideway has its bearing portion 22 formed separately for convenience and inserted in a recess in the guideway 21 and secured therein as by means of screws 23, 24 indicating the grooved track with which cooperates a correspondingly formed part or collar 25 preferably constructed of insulating material such as phenol condensation product, rubber or similar composition. Collar 25 is formed centrally with a circular opening 26 the sides of which are curved as at 27 and faced with a sheet of yieldable material 28 such, for example, as cork. In the present instance collar 25 is particularly adapted for sup-

porting engagement with an X-ray tube 29 of the so called "Coolidge" dental type having a generally tubular shape with a spherically enlarged portion 30 intermediate its ends. The tube parts shown and referred to in the present instance form the protective glass shield within which the tube proper is located, the light rays being of course projected from the nozzle end of the tube toward the left as shown in Figure 1. This end of the tube is therefore inserted in the opening in collar 25 with the latter in gripping engagement with the corresponding side of the spherical enlargement 30. A corresponding collar 31 is placed on the other end of the tube in engagement with the opposing surface or side of the spherical portion 30 and these collars 25 and 31 are formed with perforated bosses thru which are passed tie rods 32 for drawing the parts together and clamping the tube therebetween so that the latter is securely gripped and held. It is apparent from this construction that the tube and collars 25 and 31 are rigidly assembled and that as collar 25 is slidably adjusted in the frame loop 20, the tube is pivotally adjusted about the object in the manner described.

Means are provided for adjusting the tube in the frame loop as described comprising preferably a boss 33, Figure 4, formed on the inserted bearing portion 22 of the upper guideway 21 in which boss is rotatably carried a spindle 34. Fixed on the spindle is a pinion 35 meshing with a rack 36 fixed on part 25 as by means of screws 37 which also support on part 25 a clip 38 having a flange 39 extending under the end of spindle 34. The latter has a slight longitudinal sliding movement in its bearing for engagement with a series of recesses 40 in the flange 39 and it is apparent that spindle 34 may be rotated by means of a hand piece 41 to adjustably slide the tube along the guideway and that with the parts so adjusted the spindle may be slid longitudinally into locking engagement with one of the recesses 40 to lock the parts in an adjusted position. In the present instance there are three such recesses 40, one located centrally of the guideway and one on either side of the central position for making the different views referred to above. Collar 25 preferably has fixed thereon a holding sleeve 42 in which is supported the usual adapter or nozzle 43.

The tube to which the invention is adapted in the present instance has an upwardly extending flange 44 in which the filament is located. The filament and its connection being more or less delicate in construction, there is provided a protective hood 45 of metal or other rigid material covering the upper end of the filament flange and thus protecting the latter and its contents, the hood being clamped to the flange as by

means of tying clips 46 fixed at one end to the hood and at the other to the adjacent tie rods 32.

The pivotal adjusting movement of the loop shaped frame 19 on the supporting arms 16 is preferably limited as by means of a stud 47 on an end 18 of the frame which engages with opposing stop shoulders 48 on the adjacent supporting arm 16. The swinging movement of the frame on the supporting arm is thus limited so that the tube cannot be swung far enough to cause its outer or radiator end to which the high tension electrical connection is attached to approach dangerously near the supporting sections. It is to be noted that the end portions of the loop shaped frame are carried opposite the other collar 31 or substantially into vertical alignment with the center of gravity of the tube and its attachments, so that the tube tends to remain in any position in which it is swung on the trunnions 17 assisted by the slight friction of the connections. The location of the pivotal axis formed by trunnions 17 above the axis of the tube as shown in Figure 1 is also advantageous as tending to throw the outer high tension end of the tube farther from the supporting section 15 when the tube is swung to carry its outer end upwardly.

It is apparent from the above construction that the tube may be readily adjusted along the guide-ways 21 and also easily swung by a light pressure of the hand about the trunnions 17 and also about the pivotal axes of the sections 14 and 15. The shape and arrangement of the various parts are such as to effectively enclose and protect to a large degree the fragile tube and its connections. This is accomplished not only by the forked arms 16 which embrace the tube but also by the extension of the end portions of frame 19 from their pivotal connections with arm 16 along the sides of the tube and by the encircling of the tube by the looped portion of the frame. The collars 25 and 31 with their tie bolts 32, and also the hood 25 and clips 46 contribute to the same result.

In Figures 6 to 8 is shown a modified form of construction for the loop shaped frame, in which the frame, indicated at 49, has a substantially rectangular looped portion 50 with unitary end portions 51 extended to enclose the tube on opposite sides. These end portions are adapted for pivotal connection at their extremities 52 with forked supporting arms such as indicated at 16 in the preferred embodiment. In this case however, while the pivotal points are arranged to fall opposite the center of gravity of the tube, they are not raised vertically above the same as in the preferred form. The frame loop is formed at its opposite sides with guide-ways 53 curved on an arc as before and provided with tracks on which slides a collar 54

provided with openings 55 for tie rods engaging with a similar collar between which and collar 54 the tube is clamped as previously described. A rack and pinion device is provided in this form also for sliding the tube in the frame loop.

The operation of the apparatus has been explained in connection with the description of its construction and it is apparent that the apparatus is simple and practical in character, affording an effective means for gripping and supporting the light source, in a manner permitting easy adjustment of the latter in a variety of positions, while the disposition of the parts is such as to afford at the same time a large degree of protection for the fragile light source against injury by inadvertent blows or collisions in use.

We claim as our invention—

1. A light projecting apparatus comprising a support, a loop-shaped frame adjustably carried by said support and provided at opposite sides thereof with arcuate guide means, a body including a source of light, a

second frame supporting said body and slideable in said first frame on said guide means to different radial operating positions, a rack on one of said frames and an intermeshing pinion on the other, and means for rotating said pinion to adjust said second frame and light source.

2. A light projecting apparatus comprising a support, a frame adjustably carried by the support, a body including a source of light, a second frame supporting said body and slideable on said first frame to different operating positions, a rack on one of said frames and a rotatable and longitudinally slideable spindle on the other frame provided with a pinion meshing with said rack and with a portion slideable into locking engagement with recesses in the frame on which said rack is carried.

3. A light projecting apparatus comprising a support, a frame adjustably carried by the support and comprising spaced opposite sides formed with arcuate guideways, a body including a source of light, spaced parts adjustably connected with each other for clamping engagement with opposed surfaces of said body, one of said parts being slidably supported on said guideways for move-

ment to different radial positions on said frame, a rack on one of said parts and means comprising a pinion on the frame meshing 55 with the rack for moving said parts and body to different positions.

4. A light projecting apparatus comprising a support, a body including a source of light, spaced parts in clamping engagement 60 with opposite surfaces of said body, and a frame having means adjacent its center for movably supporting one of said parts and said body and having its ends extended opposite the other of said parts and adjustably connected with said support.

5. A light projecting apparatus comprising a support, a body including a source of light, a supporting part fixed to said body, and a frame having centrally thereof an 70 arcuate guide portion extending transversely of said body and slidably supporting said part and having end portions extended along opposite sides of said body to enclose and protect the same and pivotally connected 75 with said support.

6. A light projecting apparatus comprising a support, a body including a source of light, a frame having a central loop portion encircling said body and having end portions 80 extended along opposite sides of said body to enclose and protect the same, connections between said support and the ends of said frame movably supporting the latter, and cooperating means on said body and opposite 85 sides of said frame loop portion for adjustably supporting said body.

7. In a light projecting apparatus, a body comprising a source of light, spaced supporting parts clamped to opposing surfaces of 90 said body, a frame having a central loop portion encircling said body with opposite sides provided with spaced guideways slidably supporting one of said parts, rack and pinion means for adjusting said part in the frame 95 loop, end portions on said frame extending transversely of said loop portion along the sides of said body opposite the other of said parts, and a forked support having arms extended on opposite sides of said body and 100 pivotally connected with the end portions of said frame.
